10 Claims

ABSTRACT OF THE DISCLOSURE

This invention relates to an apparatus for launching balloons that includes an array of anchor points arranged in a substantially circular pattern around a payload at the center, a load line connected between the payload and balloon train, a bridle consisting of two equal-length cables extending from the point of attachment of the load line and balloon train downwardly and outwardly in divergent relation to a pair of the anchor points on the opposite side of the payload, and a movable winch capable of circumnavigating the payload having a mainstay releasably attached to the latter. The method comprises using the bridle to keep strain off the load line until just prior to the actual launch, at which point the load is preferably divided almost equally therebetween, and repositioning the bridle to accommodate changes in wind direction by moving the winch vehicle to alternately transfer the entire load from one bridle cable to the other so that each, in turn, becomes slack and can be reconnected at a different anchor point.

Thin, strong plastic films have made it possible to conduct balloon-borne experiments at altitudes well over 100,000 feet, which means the instrument package lies above all but a fraction of 1% of the earth's atmosphere. Balloons for this purpose are quite large, having a volume of several million cubic feet, if they are to lift a heavy payload to these extreme altitudes. The payloads, on the other hand, run generally from something a little less than 1000 pounds to as high as 10,000 pounds.

Launching a balloon of this type is a difficult and time-consuming operation that demands ideal weather conditions and a highly-experienced launch crew. To obviate the necessity for having to cope with unfavorable wind conditions, the preferred launch sites provide both calm weather and natural shelter such as, for example, at the base of a high cliff or bluff. Even with these precautions, controlling the balloon in strong gusty winds becomes very difficult and not infrequently results in damage to the payload. Problems such as this are not easily solved but, in the meantime, steps need to be taken to protect the payloads.

Balloon-borne payloads quite generally consist of delicate scientific instruments that are extremely costly and, therefore, a great deal more important to protect against damage than the balloon train that carries it aloft which, by comparison, is not worth very much. A payload is particularly vulnerable during launch because of its close proximity to the ground. Once airborne, there remains at least some prospect of parachuting it safely back to the ground; however, while being launched, the payload can be severely damaged and even destroyed as a result of an uncontrollable balloon by being dropped, dragged, bounced or flung against some obstacle and, up to the

2

present time, there was little that could be done to save it once the launch procedure has commenced. Actually, even a sharp tug on the load line by a rapidly ascending balloon train might be enough to jar delicate instruments and damage them so that they will not perform properly thus, oftentimes, causing the whole experiment to fail.

Wind blowing across the surface of the launch site is, perhaps, the single most important environmental factor that one must be able to cope with in order to protect the payload from damage during launch. The launch procedure is a lengthy one requiring that the balloon train be laid out along the ground and a small fraction of its total volume filled with helium. A mainstay restrains the balloon train and is payed out from a winch until the train is successfully deployed; whereupon, the mainstay is disconnected and the payload is lifted aloft. All during this time, an unexpected increase in wind velocity or a change in wind direction can be disastrous to the payload which is already coupled thereto. Even slight damage to the payload means delaying the launch while a check is made to see that everything is operating correctly.

It has now been found in accordance with the teaching of the instant invention that the aforementioned difficulties can, in large measure, be avoided by isolating the payload from the balloon train by a novel bridle that carries the balloon train tension by itself until just prior to the actual launch, at which time the lift load is distributed between said harness and the load line. If, perchance, a squall or some such unforeseen condition develops unexpectedly, the load line can be instantly disconnected from the bridle so that the payload is protected from whatever mishap may befall the balloon train. The balloon train is restrained and slowly deployed by a movable winch located at the opposite side of the payload from the bridle. A shift in the wind direction can be accommodated by moving the winch vehicle around the circle so that the anchor line or mainstay places the balloon train in position to produce slack in one cable of the bridle; whereupon, it can be removed and fastened to another anchor point in the circular array thereof while the lift load is carried entirely by the taut one. Reversal of this procedure is used to relocate the other bridle cable so that, upon completion of the operation. The balloon train is positioned directly upwind and the bridle downwind of the payload. The mainstay is disconnected during erection, preferably at the point where the lift is being shared between the bridle anchors and load line and, once the load is airborne, the bridle can be released.

It is, therefore, the principal object of the present invention to provide a novel method for launching balloons where the payload is isolated and may even be disconnected from the balloon train until just prior to the actual launch.

A second objective of the invention herein disclosed and claimed is the provision of a balloon launching apparatus that can quickly and easily be changed to accommodate a shift in wind direction without disturbing the payload.

Another object is to provide a launch apparatus of the type aforementioned that includes a bridle which carries the entire lift load until just prior to launch.

Still another objective is the provision of a circular array of bridle anchor points that cooperates with a vehicle-mounted mainstay winch to provide means for alternately slackening off the bridle cables so that they can be relocated in different positions.

A further object is to provide a balloon-launching ap-

paratus and method of using same that is simple, easy to use, versatile, inexpensive, safe, foolproof, protective of the payload, and productive of a smooth gentle launch.

Other objects will be in part apparent and in part pointed out specifically hereinafter in connection with the description of the drawings that follows, and in which:

FIG. 1 is a diagrammatic perspective showing the final stages in the balloon launching sequence of the present invention;

FIG. 2 is a top plan view showing in schematic form the first step in the method used to change the bridle anchor points so as to accommodate a change in wind direction; and,

FIG. 3 is a top plan view like FIG. 2 showing the final step in the reanchoring sequence.

Referring first to FIG. 1 of the drawings for a detailed description of the present invention, it will be seen that, in the particular form illustrated, the balloon train, which has been designated broadly by reference numeral 10, is of the dual balloon type that includes both a launch balloon 12 and a main balloon 14 connected to one another in end-to-end relation by a suitable transfer fitting 16 located therebetween. Also considered a part of the balloon train 10 is the load line 18 which, in the particular form shown, comprises a yoke-type harness connected at its apex to the lower end of the main balloon 14 and diverging therefrom to points of attachment on opposite sides of the payload 20. The balloon train could, of course, include only a single large balloon rather than the two shown without materially altering either the launch apparatus or method of using same in accordance with the teaching of the instant invention although, admittedly, the techniques of filling the balloons may vary with the different types of balloon trains, but these aspects of the launch sequence are old in the art and form no part thereof.

Using the payload 20 as the center, a plurality of "deadmen" 22 are arranged in substantially equi-angularly spaced relation therearound to form a circular anchor array that has been indicated in a general way by reference numeral 24. The balloon train 10 is attached to this circular anchor array by a bridle that has been broadly designated by reference numeral 26 and which comprises a pair of cables 28 and 30 of substantially equal length. These cables diverge from the point of connection between the main balloon and payload harness downwardly and outwardly to a circumferentially displaced pair of the deadmen 22 that lie downwind of the payload.

The inflated launch balloon 12 is gradually allowed to rise, lifting the deflated main balloon off the ground by paying out an anchor cable or so-called "mainstay" 32 from a mobile winch 34 which, in the particular form shown, is mounted on the bed of a truck 36 that circles the anchor array 24 and payload 20 at a considerable radial distance therefrom, although somewhat less than the overall length of the balloon train 10. It is important that the winch 34 be mobile as will appear presently; however, obviously, it need not be mounted on a truck but could, for example, roll along a monorail or some other type of more permanent installation.

Now, the ideal launch condition is that shown in FIG. 1 where the balloon train 10 is deployed directly upwind of the payload 20 and the bridle 26 directly downwind thereof, the wind direction having been indicated by the arrow. The main balloon 14 is laid out along the ground, the mainstay connected to the transfer fitting 16, and the launch balloon 12 inflated in the usual manner. All during these steps in the launch procedure, the bridle 26 is connected to the balloon train, but there is no need to attach the load line or harness 18 as yet although, obviously, it may be so connected if desired.

Next, the winch 34 is actuated to pay out sufficient anchor line or mainstay 32 to loft the launch balloon 12 to an elevation which will raise the main balloon and remaining elements of the balloon train off the ground, such

a condition having been indicated by full lines in FIG. 1. At this point, the actual moment of launch is imminent and the payload 20 can be connected to the balloon train by means of its harness 18, it being most unlikely that any shift in wind direction or abrupt increase in wind velocity will occur during the few minutes remaining before the balloon train is cut free. Note, however, that with both the mainstay 32 and bridle 26 still connected, the payload 20 remains essentially isolated from the balloon train in case of an emergency. If necessary, the payload harness can yet be disconnected and the balloon train can be relocated to accommodate a change in wind direction regardless of whether the payload is attached thereto or not.

The next stage in the normal launch procedure is that at which the slack is removed from the payload harness and the first strain is placed thereon, such a condition having been shown in FIG. 1 by the broken lines adjacent the full line representation. The relative lengths of the harness and bridle cables are selected such that, as the apex of the latter moves into position above the payload, the lift load is distributed or shared therebetween. Actually, the mainstay 32 may be released from the transfer fitting 16 at any time after the payload harness becomes taut indicating that it has begun to share the lift load. Obviously, at this point the payload will not be jerked off the ground as would be the case if the mainstay were released while slack remained in the payload harness. Also, with the harness sharing the lift load with the bridle, the payload is ready to be lifted off the ground. Now, as aforementioned, the mainstay can be relaxed at any time after the payload harness is carrying part of the lift load; however, tests have shown that the best procedure in terms of reliability and acceptable payload acceleration is to release the mainstay when the lift load is shared approximately equally between the harness and bridle.

The final step in the launch procedure is, of course, to release the bridle from the anchor array. This is done after the mainstay has been disconnected and at any time after the payload is airborne. The above-described launch procedure is smooth and reliable offering maximum protection to the payload, which remains effectively isolated from the launch system until the final stages of the operation.

Next, with reference to FIGS. 2 and 3, the procedure for reorienting the balloon train to compensate for a change in wind direction will be set forth in detail. Assume that the original wind direction was radially inward toward the payload 20 along the line of the arrow paralleling the main balloon 14 in FIG. 2. Next, assume a slight change in the wind direction to that indicated by the broken line arrows in both FIGS. 2 and 3. As the wind changes direction, the launch balloon 12 will be deflected so as to swing sideways until it occupies a position something like that shown in broken lines in FIG. 2 immediately adjacent the full line position. When this occurs, the launch crew must relocate the bridle so as to connect it more or less directly downwind of the balloon train in accordance with the new wind direction.

The first step in relocating the bridle is to move the winch vehicle 36 from position A in FIG. 2 clockwise to position B shown in broken lines. In so doing, cable 28 of the bridle 26 becomes slack, while the other cable 30 carries the full lift load. Cable 28, therefore, can be disconnected from deadman 22a of the anchor array and reconnected to deadman 22b.

From position B in FIG. 2, the winch vehicle moves counterclockwise down to position C shown in full lines in FIG. 3 where cable 30 of the bridle becomes slack and cable 28 thereof carries the entire lift load. Here, as before, cable 30 is removed from deadman 22c of the anchor array and reconnected at deadman 22d, thus placing the bridle in position such that the wind is blowing in a direction essentially bisecting the angle formed between the legs thereof.

The final step in the sequence is to move the winch vehicle 36 to position D shown in broken lines in FIG. 3 when the balloon train 10 is directly upwind of the payload. In actual practice, relocating the bridle in accordance with the above-described procedure can be accomplished in less than ten minutes under ordinary circumstances. Note also, this can be carried out with the payload harness connected to the balloon train so long as the latter remains slack.

In closing, a few general comments concerning the construction and geometry of the system as above-described would be helpful. First of all, it should be obvious that one of the essential features of the system is a pair of arcuately-adjustable anchor points for the free ends of the bridle so that the legs thereof may be placed on the downwind side of the payload in divergent relation to one another such that the included angle therebetween is essentially bisected by a line passing through the payload in the direction the wind is blowing. It is not necessary, therefore, that the anchor ring consist of a plurality of angularly-spaced anchor points as the same thing could be accomplished with a circular rail of some sort carrying rolling anchor blocks that could be fastened at various points therewith. The system above-described, including the circular array of deadmen, is, of course, considerably less expensive than some elaborate rail system and, while it does not provide an infinite variety of anchor point locations, there are generally enough selections available to answer the needs of the launch system.

The legs of the bridle are preferably connected on the downwind side of the payload which means, of course, that they will be spaced apart angularly less than 180°. If connected at opposite diametric points on the anchor point circle, the length of the load-carrying harness would have to be selected such that it became taut when the apex of the bridle moved into position directly over the payload; otherwise, it would not be possible to transfer any of the lift load to the harness before releasing the bridle, nor would it be possible to leave the harness slack until the final stages of the launch. These difficulties are eliminated quite easily by simply connecting both legs of the bridle to anchor points downwind of the load. In so doing, the harness can remain slack until the final stages of the launch; yet, become taut so as to assume a share of the lift load long before the apex of the bridle reaches a position directly over the payload. On the other hand, once such a position is reached, the payload will already be airborne so that the bridle can be released from the anchor points without danger of the payload striking the ground as the balloon swings downwind overhead.

What is claimed is:

1. The apparatus for launching a balloon train of the type including at least one gas-filled envelope adapted to lift a load suspended from the underside thereof which comprises: anchoring means located in an essentially circular ring about the load so as to define a plurality of circumferentially-spaced anchor points; a V-shaped bridle having the apex thereof connected to the lower end of the balloon train and its legs extending in divergent relation past the load on opposite sides thereof to a pair of angularly-displaced anchor points located on the far side of the latter, said bridle being anchored such that the angle formed by the legs thereof is substantially bisected by a radial line passing through the load and extending in the direction the wind is blowing, and the length of said bridle being such that the apex thereof can move upwardly following an arcuate path from a position on the near side of the payload and clear the latter as it passes overhead; a flexible harness connecting the load to the lower end of the balloon train and to the bridle at approximately the apex of the latter, said harness being of a length selected to become taut approximately when the apex of the bridle reaches a position directly above the load; winch means movable in an arcuate path outside the anchor point ring on the near side of the payload;

and, releasable anchor cable means forming a mainstay extending from the winch means to the gas-filled envelope of the balloon train, said mainstay and winch means cooperating upon actuation of the latter to control deployment of the balloon train until the lift thereof is shared by the harness and the load is airborne whereupon said mainstay may be released followed by the bridle.

2. The apparatus for launching balloons as set forth in claim 1 in which: the legs of the bridle are both of a length greater than the radius of the anchor point circle and approximately equal to one another.

3. The apparatus for launching balloons as set forth in claim 1 in which: the circle of anchor points and the path of arcuate movement of the winch means are substantially concentric about the load as the center.

4. The apparatus for launching balloons as set forth in claim 1 in which: the legs of the bridle are anchored on the downwind side of the payload.

5. The apparatus for launching balloons as set forth in claim 1 in which: each leg of the bridle is capable of carrying the entire lift load of the balloon train while the other of said legs is slack.

6. The apparatus for launching balloons as set forth in claim 1 in which: the winch means is movable to a position directly upwind of the payload.

7. The apparatus for launching balloons as set forth in claim 1 in which: the maximum overall length of the load and its harness measured from the bottom of the former to the top of the latter when taut is approximately equal to perpendicular distance from the center of the anchor point circle to the apex of the bridle when the latter is directly overhead.

8. The method of launching a balloon carrying a load suspended therefrom on a harness which comprises: anchoring the balloon on the downwind side of the load with a bridle adapted to keep the harness slack until the point at which the latter attaches to the balloon reaches an overhead position relative to the load, controlling the ascent of the balloon from a position upwind thereof by paying out a mainstay connected thereto until it is fully airborne, disconnecting the mainstay from the balloon following transfer of a portion of the lift developed by the latter from the bridle to the harness, and releasing the bridle after disconnecting the mainstay once the load is airborne.

9. In a balloon launching system of the type having several anchor points arranged in a ring around the load, a V-shaped bridle having the apex thereof connected to the balloon and its legs diverging to a pair of angularly-spaced anchor points on the downwind side of the load, and a mobile winch movable from one position to another on the upwind side of the load releasably connected to the balloon by a mainstay, the method for relocating the balloon into a position directly upwind of the load upon a change in wind direction which comprises the steps of: moving the winch to one side of a line bisecting the angle formed by the legs of the bridle so as to introduce slack in the leg on the same side, reconnecting said leg while still slack to a second anchor point displaced from its original anchor point in the same direction and at approximately the same angle as the new wind direction bears to the old wind direction, moving the winch back again to the opposite side of the line bisecting the angle formed by the legs of the bridle as originally positioned so as to introduce slack in its other leg, reconnecting said other leg to a second anchor point displaced from its original position in the same direction and through approximately the same angle as that through which the first leg was moved, and locating the winch at a point substantially directly upwind of the load.

10. The method of launching a balloon with a load suspended therefrom on a harness which comprises the steps of: anchoring the balloon on the downwind side of the load so as to essentially isolate same by keeping the harness slack until said balloon is fully airborne, control-

ling the ascent of the balloon from the upwind side thereof by restraining same until the slack has left the harness and a portion of the lift load is transferred thereto, releasing the restraint on the upwind side when the lift load is shared approximately equally between the harness and downwind anchor, and disconnecting the downwind anchor after the load has become airborne.
